PIPE ATTACHMENT FOR STEAM LOOMS

Filed May 17, 1922

Owen F. McEnaney.

By Lester L. Sargent

Attorney

UNITED STATES PATENT OFFICE.

OWEN F. MCENANEY, OF BROOKLYN, NEW YORK.

PIPE ATTACHMENT FOR STEAM LOOMS.

Application filed May 17, 1922. Serial No. 561,777.

To all whom it may concern:

Be it known that I, OWEN F. MCENANEY, a citizen of the United States, residing at Brooklyn, in the county of Kings and State of New York, have invented a new and useful Pipe Attachment for Steam Looms, of which the following is a specification.

The object of my invention is to provide novel means for moistening artificial fiber silk before it is woven into cloth and used for dress goods, whereby a finer cloth can be produced and the machines can be run faster and more production obtained. I attain these and other objects of my invention by the mechanism illustrated in the accompanying drawings, in which—

Figure 1 is a perspective view of the invention applied to a loom;

Fig. 2 is a detail side elevation of the thread moistening device; and

Fig. 3 is a vertical longitudinal section of same.

Like numerals indicate like parts in each of the several views.

Referring to the accompanying drawings, 1 indicates the main frame or base of the loom. The threads 5 are unwound from bobbins 2 and travel through the wire guides 3 and thence through the moistening devices 8 to the weaving mechanism 4 of the loom. I provide a suitable steam pipe 6 through which steam is delivered through the auxiliary pipe 7 and thence through the steam inlet 13 into the steam chamber 12 of the moistening device 8, of which there may be any suitable number.

Moistening devices 8 consist of an outer cylindrical wall 9, an inner spaced cylindrical wall 10, and cap members 11, thereby forming the steam chamber into which steam is supplied directly from steam inlet 13, which is threaded at 14 and attached to the steam auxiliary pipes 7. Mounted in each end of moistening devices 8 are porcelain plugs 17 having a longitudinal channel 18 in each through which the thread 5 of the fiber silk passes, the smooth surface of the porcelain preventing any injury to the thread. Inner wall 10 is provided with openings 15 to admit steam into the central

chamber 16 and moisten the fiber silk thread which is continuously traveling through that chamber.

I provide a discharge spout 19 opening out of the steam chamber 12 for the discharge of steam that has condensed into water. I provide funnels 20 under the moistening devices 8 to receive water discharged from spouts 19, the water thence being carried away through the pipes 21 which are in communication with funnels 20, as shown in Fig. 1.

The operation of the invention may be apparent from the foregoing description and accompanying drawings.

Any suitable number of the moistening devices 8 are arranged around the main frame of the loom. The threads are fed from the bobbins 2 through the wire guides 3 and through the moistening devices 8. The steam which enters chamber 12 from pipe 7 and inlet 13 percolates through the opening 15 into the inner steam chamber 16 through which the fiber silk threads 5 are continuously traveling in their path to the weaving mechanism of the loom. The moistening of the fibers by the steam before the fibers are woven into the cloth results in an improvement in the quality of the cloth and makes it possible to run the machines faster and therefore get more production than would otherwise be possible.

What I claim is:

1. In an attachment for looms, a thread moistening device consisting of a cylindrical shell, an inlet opening into said shell for the admission of steam, an inner cylindrical shell, said shell having openings in its wall, thread-guiding elements secured to the ends of said shell, and a drain spout opening out of the outer shell.

2. In combination with the apparatus described in claim 1, steam pipes to which the inlet is detachably secured for supplying steam to the thread-moistening device.

3. In combination with the device described in claim 1, steam pipes to which the inlet is detachably secured for supplying steam to the thread-moistening device, a funnel positioned beneath the discharge

spout of the moistening device, and a drain pipe to which said funnel is attached.

4. In a thread-moistening device of the class described, a hollow chamber having spaced walls to form an inner and outer chamber, perforations in the inner wall to admit steam from the outer into the inner chamber, a steam inlet opening into the outer chamber, a discharge spout opening out of

the bottom portion of the outer chamber, 10 channeled thread-guiding elements of suitable smooth surfaced material mounted in opposite ends of the inner chamber to guide the thread therethrough, and steam pipes to which the device is attached and supplying 15 steam to same.

OWEN F. McENANEY.
